UNITED STATES PATENT OFFICE.

HENRY A. DEAN, OF ROME, GEORGIA.

HEEL-SWEEP.

1,130,489.

Specification of Letters Patent.

Patented Mar. 2, 1915.

Application filed June 30, 1913. Serial No. 776,691.

To all whom it may concern:

Be it known that I, HENRY A. DEAN, a citizen of the United States, residing at Rome, in the county of Floyd and State of Georgia, have invented certain new and useful Improvements in Heel-Sweeps; and I do declare the following to be a full, clear, and exact description of the invention, such as will enable others skilled in the art to 10 which it appertains to make and use the same.

This invention relates to plows, and more especially it is a scraping attachment adapted to be connected with the plow beam or plow-stock, and used particularly in the cultivation of cotton, corn, and grain. In other words, it is an improvement on that line of devices known as "heel sweeps."

The purpose of the present invention is 20 to strengthen sweeps of this kind at the points where they are weakest, and yet to do so without increasing the weight.

The invention likewise aims to provide a sweep so constructed as to cause its angle 25 and its arms to travel equi-distantly into the earth.

I have in mind the well-known "Terrell" heel sweep patented in 1893, Number 504375; and the present invention includes the principles of construction therein contained, with certain additions and amplifications as 30 will be set forth in the following specifications and claims, and are shown in the drawings wherein—

Figure 1 is a plan view of this improved heel sweep. Fig. 2 is a cross section on the line 2—2 of Fig. 1, and Fig. 3 a cross section through the center of the line 3—3 of Fig. 1. Fig. 4 is an upper edge view looking in about the direction indicated by the arrow in Fig. 2. Fig. 5 is a sectional view showing slight modifications.

As is well known to those familiar with this art, heel sweeps are scraping devices 45 adapted to be attached to the lower ends of the plow beam or plow-stock, and the common practice is to manufacture them by rolling strips of iron of the proper cross section, cutting the strips into lengths, and 50 then giving each length a bend at about its mid-length so as to produce a substantially V-shaped structure whose apex is flattened and moves forward as the heel sweep is in use. The bend is made on a line oblique 55 to the plane of the length of the strip, so that eventually each fluke or leaf of the

V-shaped member stands inclined at about an angle of 45° to the horizontal, with the result that there is a fullness of metal near the apex, it is bulged to the front, and the angle of the flattened portion which is attached to the plow-stock is greater than 45°. As usually constructed, these devices are susceptible of being bent by the farmer or other user who has indifferent means of heating them, and therefore they are made of such material that they can be bent so that he may accommodate them to the work they are to perform. It follows from this fact that the material from which the sweeps are produced must be stout enough to withstand rough usage and yet pliable enough to permit them to be bent by the user, even though he may have to heat them slightly. The Terrell heel sweep was 75 thickened at the center of the strip and grew thinner toward each edge thereof, the lower edge being ground on its rear side and also on its front side to produce a cutting edge. On this understanding I will 80 proceed with a description of the details of the present invention.

The body portion of the metal strip of which my improved heel sweep is made, designated as 1 in the drawings, is about a 85 quarter of an inch in thickness, and this thickness obtains for about one-half the width of the strip, being the central half and below the uppermost quarter and above the lowermost. The latter is beveled on its 90 rear side as at 2, and the bevel is carried completely downward to the cutting edge 3. The remaining one-quarter of the width of the strip is thickened as at 4, by producing a bead or rib on the rear face of the body 1 95 along its upper edge; and in the modified form shown in Fig. 5 this bead or rib has a groove 5 along it, virtually dividing the same into two beads or ribs. In Figs. 1 and 4 it will be seen that after the strip of metal 100 is bent into V-shaped form, or perhaps in the act of bending it, a bulge 6 is produced at each side of what might be called the flattened center 7; and particular attention is directed to the fact that the bead or rib 4 105 throughout the length of said center is thicker than elsewhere as indicated by the reference numeral 4', this thickness being carried around above the bulges 6 and out into the blades or flukes for a short distance. 110 The particular purpose of this increase in thickness of the bead is to give the heel

sweep strength at what would otherwise be its weakest point, because the flattened center 7 is pierced with an opening 8 through which passes the bolt by means of which the 5 sweep is connected with the plow-stock in a manner not necessary to illustrate. If the center is sufficiently flattened on both its front and rear faces, either face may be attached to the plow-stock, but ordinarily 10 the stock goes behind the center in the well known manner; however this detail need not be amplified. As shown in Fig. 2, the entire strip is by preference dished a little throughout its width at both ends and at its center, 15 and in the finished article illustrated in Fig. 1 this dish is presented forward so that the cutting edge 3 moves almost edge on through the soil. However, I do not wish to be unnecessarily limited to this dishing of the 20 body, and Fig. 5 is shown as absolutely straight. In any event, I would make the front and rear faces of the body portion 1 parallel, and I would carry the flat or slightly dished front face clear to the upper 25 edge and clear to the lower edge, whereas the rear face of the rib might be flat, rounded, grooved as shown at 5, or of other configuration and the rear side or bevel 2 is preferably flat although that also might be 30 of slightly different shape. When the device becomes dull it is ground along this bevel in a manner well understood.

With a heel sweep as thus constructed, the greatest strength exists along the upper edge 35 of the blade or fluke and especially around the bend at the upper edge of the central portion. The blades are thickened by the ribs 4, and the central portion is not only thickened by said rib but the rib itself is 40 made a little thicker as at 4' to offset the weakening produced by the opening 8. Yet the addition of this rib and the slight increase of its thickness at its center, does not materially add to the weight of the entire 45 device, nor to its cost; and the disposition of the rib along the upper edge of the device

does not prevent the farmer or user from bending its lower edge in case he desires to sweep a slightly wider or narrower path, because he would in that event probably 50 bend the outer ends of the cutting edges either outward or inward, along their lower edges. If, however, he should desire to materially alter the shape and size of the device, it is possible for him to heat it and 55 then bend it at will if it is made of the proper material, as the addition of the rib 4 throughout each blade or fluke and the thickened rib 4' around the center, does not prevent. 60

I do not wish to be limited to the material or the proportion of parts.

What I claim as new is:

1. A heel sweep for cultivation, comprising a single sheet of metal bent into substantially V-shape in plan view, the outer and front side of the sweep thus formed being inclined upwardly and rearwardly, and being dished at its angle and for a short distance from each end thereof, said sweep having its rear side tapering downwardly and forwardly and being provided with a reinforcing rib at the upper and rear portion thereof, substantially as described. 65

2. The herein described heel sweep formed 70 of a single strip of metal bent into substantially V-shape in plan view, the outer side of the sweep thus formed being inclined upwardly and rearwardly and being dished at its angle and at its two ends, whereby said 75 angle and ends will be drawn equi-distantly into the earth, and the portion of said outer side between said angle and said ends being flat.

In testimony whereof I have hereunto set 80 my hand in presence of subscribing witnesses.

HENRY A. DEAN.
